UNITED STATES PATENT OFFICE.

ROLLA C. SHAW, OF INGLEWOOD, CALIFORNIA.

DESIGN FOR A WIND-DEFLECTOR.

55,489.

Specification for Design. Patented June 15, 1920.

Application filed March 25, 1920. Serial No. 368,756. Term of patent 7 years.

To all whom it may concern:

Be it known that I, ROLLA C. SHAW, a citizen of the United States, residing at Inglewood, county of Los Angeles, and State of California, have invented a new, original, and ornamental Design for Wind-Deflectors, of which the following is the specification, reference being had to the accompanying drawing, forming a part thereof.

Figure 1 is a perspective view of the wind deflector;

Fig. 2 is a view of same as seen in front elevation;

Fig. 3 is a view in vertical section as seen on the line 3—3 of Fig. 2;

Fig. 4 is a horizontal section as seen on the line 4—4 of Fig. 2.

I claim:

The ornamental design for a wind deflector, as shown.
